UNITED STATES PATENT OFFICE.

VICTOR E. LANE, OF DETROIT, MICHIGAN, ASSIGNOR TO MICHIGAN SMELTING AND REFINING COMPANY, OF DETROIT, MICHIGAN, A CORPORATION OF MICHIGAN.

DIE-CASTING MACHINE.

Application filed April 4, 1921. Serial No. 458,482.

To all whom it may concern:

Be it known that I, VICTOR E. LANE, a citizen of the United States of America, residing at Detroit, in the county of Wayne and State of Michigan, have invented certain new and useful Improvements in Die-Casting Machines, of which the following is a specification, reference being had thereto in the accompanying drawings.

10 The invention relates to die casting machines and has for one of its objects the provision of a construction in which the mold sections are horizontally movable toward and away from the nozzle; in which there is 15 means for positively moving the sections toward the nozzle and for yieldably moving the sections away from the nozzle; and in which there is means between the holders of the mold sections for yieldably separating 20 the same. Other objects of the invention reside in the means for actuating the plunger slidably mounted in the cylinder communicating with the nozzle. Further objects of the invention reside in the novel features of 25 construction and combinations and arrangements of parts as more fully hereinafter set forth.

In the drawings:

Figure 1 is a top plan view of a die casting machine embodying my invention;

Figure 2 is a longitudinal central sectional view partly in elevation thereof;

Figure 3 is a similar view showing the mold sections and molten metal plunger 35 in different positions of adjustment from those shown in Figure 2.

Figure 4 is an end view.

1 is a pot containing the molten metal and 2 is a male nozzle for the passage of 40 molten metal mounted upon the pot and communicating with the pump 3 for forcing the molten metal in predetermined amounts through the nozzle. 4 is a sectional mold which as shown comprises the inner and 45 outer die blocks 5 and 6 respectively which cooperate to form the mold cavity. 7 is the holder for the inner die block having the female nozzle 8 mounted thereon for 50 cooperating with the male nozzle 2, and also the passageway 9 therethrough for placing the mold cavity in communication with the female nozzle. The outer die block holder 10 and the inner die block holder 7 55 slidably engage at their corners the parallel

horizontally extending rods 11 which are 55 mounted in the standards 12 of the die casting machine frame.

For moving the outer and inner die blocks 10 and 7 respectively as well as the female nozzle 8 to bring the die blocks into engagement with each other to form the mold cavity and to bring the female nozzle into engagement with the male nozzle 2, there is the cylinder 13 mounted upon the frame and the plunger 14 slidably engaging in the 60 cylinder and having the spider 15 at the outer end of its rod 16, which spider slidably engages the parallel rods 11 and is adapted to abut the outer die block holder upon outward movement of the plunger in 65 the cylinder.

For moving the outer and inner die blocks as well as the female nozzle horizontally away from the male nozzle to withdraw the metal gate formed in the male nozzle, I have 70 provided the coil springs 17 surrounding the parallel rods 11 and abutting the standard 12 near the inner end of the pot 1 and the face of the inner die block holder adjacent to the pot. I have also provided 75 the coil springs 18 surrounding the parallel rods 11 and abutting the adjacent faces of the outer and inner die block holders 10 and 7 respectively whereby the latter are separated and the outer and inner die blocks are 80 moved away from each other to permit of removing the casting. The arrangement is such that upon return movement of the plunger to original position, the coil springs 85 18 separate the mold sections 5 and 6 and the coil springs 17 move the inner die block 90 holder 7 and the female nozzle 8 away from the male nozzle 2.

With the construction as thus far described it will be seen that by permitting 95 fluid, such as water, under pressure to enter the base end of the cylinder 13, the plunger 14 will be moved outwardly to move the die block holders 10 and 7 horizontally toward the male nozzle 2, compressing the coil 100 springs 18 and 17 and bringing the die blocks 6 and 5 into engagement with each other and the female nozzle 8 into engagement with the male nozzle. Upon permitting the entrance of the fluid under pressure into the outer end of the cylinder, the plunger will be returned to its original position and the coil springs will expand to 105

their original positions as shown in Figure 3 forcing the die block holders away from each other to separate the mold sections and also forcing the inner die block holder with 5 the female nozzle away from the male nozzle to separate the two nozzles.

The pump 3 for forcing the molten metal into the mold, comprises the cylinder 19 secured to the bottom of the pot 1 and located 10 beneath the molten metal and also comprises the plunger 20 slidably engaging in the cylinder. The inner end of the cylinder communicates with the male nozzle 2 by means of the upwardly extending passage- 15 way 21. 22 is a transversely extending aperture in the outer end of the plunger and 23 is a rock arm extending downwardly into the molten metal and having the rounded end 24 engageable in the aperture 22, the 20 arrangement being such that upon rocking of the rock arm from the position shown in Figure 2, to the position shown in Figure 3, the plunger will be moved outwardly and in its outer position, permits of the entrance 25 of the molten metal into the cylinder 19 and passageway 21 through the opening 25 between the inner end of the plunger and the outer end of the cylinder. This opening is preferably formed by cutting away a portion 30 of the inner end of the plunger. 26 is a rock shaft above the pot 1 and is actuated by means of the rock arm 27 pivotally connected to the rod 28 of the plunger 29, which latter is reciprocable, within the cylinder 30. 35 To permit of swinging the rock arm 27 through its arc, the cylinder 30 is pivotally mounted upon its support 31 as at 32. Fluid under pressure is also alternatively admitted into the opposite ends of this cylinder for 40 actuating the plunger in opposite directions.

What I claim as my invention is:

1. The combination with a horizontally extending nozzle for the passage of molten metal, of a sectional mold having horizontally movable sections, the inner of said sections having a passageway therethrough for placing the cavity within said mold in communication with said nozzle, and yieldable means for moving said sections horizontally away from said nozzle and for separating said sections from each other. 45

2. The combination with a horizontally extending nozzle for the passage of molten metal, of a sectional mold having a pair of horizontally movable sections, the inner of said sections having a passageway therein for placing the cavity within said mold in communication with said nozzle, and coil springs engaging the inner face of said 50 inner section and engaging the adjacent faces of both of said sections for yieldably moving both of said sections horizontally away from said nozzle and for separating said sections from each other. 55

3. The combination with a nozzle for the

passage of molten metal, of a pair of inner and outer cooperating die blocks, means secured to said outer die blocks for moving both of said die blocks toward said nozzle and yieldable means engaging said die blocks 70 for separating the same from each other and moving said inner die block away from said nozzle.

4. The combination with a nozzle for the passage of molten metal, of a pair of cooperating outer and inner die blocks, holders for said die blocks, a longitudinally movable member engageable with said outer die block holder for moving the same toward said nozzle to bring both of said die blocks 75 into contact with each other and said inner die block into contact with said nozzle, resilient means between said die block holders to separate said die blocks from each other, and additional resilient means 80 engaging the inner face of the inner die block holder for separating said inner die block from said nozzle. 85

5. In a die casting machine, the combination with a frame comprising spaced 90 horizontally extending rods, cooperating inner and outer die blocks, die block holders sleeved upon said rods, a nozzle engageable by said inner die block, a cylinder mounted upon said frame, a plunger slidably engaging in said cylinder and adapted to actuate said outer die block holder, coil springs surrounding said rods and extending between said outer and inner die block holders for separating said die blocks from each 95 other, and additional coil springs surrounding said rods and engaging the inner face of said inner die block holder for actuating the latter to separate said inner die block from said nozzle. 100

6. The combination with a nozzle for the passage of molten metal, of a sectional mold having separable sections, means for moving said sections toward said nozzle, and yieldable means for moving said sections away 110 from said nozzle.

7. The combination with a nozzle for the passage of molten metal, of a sectional mold having movable sections, one of said sections having a passage way therethrough 115 for placing the cavity within said mold in communication with said nozzle, and yieldable means for moving said sections away from said nozzle.

8. The combination with a nozzle for the passage of molten metal, of a mold having movable sections, one of said sections having a passageway therethrough for placing the cavity within said mold in communication with said nozzle, and yieldable means for moving said sections away from said nozzle and for separating said sections from each other. 120

9. The combination with a nozzle for the passage of molten metal, of a mold, means 130

for placing said mold in communication with said nozzle, and yieldable means for moving said mold away from said nozzle.

10. The combination with a nozzle for the passage of molten metal, of a sectional mold, means for placing said mold in communication with said nozzle, yieldable means for moving said mold away from said nozzle, and yieldable means for separating the sections of said mold.

11. In a die casting machine, the combination with a nozzle, of means for supplying molten metal to said nozzle, a sectional mold, a second nozzle carried by one section of said mold and adapted to engage the nozzle aforesaid for conveying molten metal into said mold, means for moving said mold in one direction to cause the nozzle carried thereby to register with the first-mentioned

nozzle, and yieldable means for moving said mold in the opposite direction to separate said nozzles.

12. In a die casting machine, the combination with a nozzle, of means for supplying molten metal to said nozzle, a sectional mold, a second nozzle carried by one section of said mold and adapted to engage the nozzle aforesaid for conveying molten metal into said mold, means for moving said mold in one direction to cause the nozzle carried thereby to register with the first-mentioned nozzle, yieldable means for moving said mold in the opposite direction to separate said nozzles, and yieldable means for separating the sections of said mold. 35

In testimony whereof I affix my signature

VICTOR E. LANE.
